UNITED STATES PATENT OFFICE

ELLIOTT J. SHAFFRANK, OF CLEVELAND, OHIO

DESIGN FOR A TRAILER CAB

Application filed June 9, 1931. Serial No. 40,141. Term of patent 3½ years.

To all whom it may concern:

Be it known that I, ELLIOTT J. SHAFFRANK, a citizen of the United States, residing at Cleveland, in the county of Cuyahoga and State of Ohio, have invented a new, original, and ornamental Design for Trailer Cab, of which the following is a specification, reference being had to the accompanying drawings, forming a part thereof.

In the drawings, Fig. 1 is a perspective view of the design, and Fig. 2 is a plan view on a smaller scale.

I claim:

The ornamental design for a trailer cab, substantially as shown.

ELLIOTT J. SHAFFRANK.
